METHOD OF CEMENTING WHIPSTOCKS IN WELL BORES

Original Filed Nov. 1, 1929

Fig. 1.

UNITED STATES PATENT OFFICE

LAURENCE C. KELLY, OF BEVERLY HILLS, CALIFORNIA

METHOD OF CEMENTING WHIPSTOCKS IN WELL BORES

Original application filed November 1, 1929, Serial No. 403,968. Divided and this application filed November 21, 1932. Serial No. 643,616.

This invention relates to a method of setting a cutter deflecting tool or whipstock in a well bore, and it is a general object of the invention to provide an improved 5 method for effectively and securely setting a whipstock in cement in a well bore.

In drilling wells it sometimes occurs that the bit meets an obstruction, or the lower end of the well bore becomes obstructed by 10 the dropping of a bit or other tool therein; and in such cases the drilling tool must be "side-tracked" to avoid the obstruction. For this purpose it is the practice to lower a whip-stock through the well bore until it 15 reaches the obstruction, the upper end of the whipstock having a diagonal deflecting surface that forms a deflecting guide for the drilling tool. After anchoring the whipstock in position, the drill is lowered 20 and upon meeting the inclined upper surface of the whipstock is deflected laterally or "side-tracked" from the original bore, cutting a slanting bore through the side of said original well bore, and thus passing 25 downwardly along one side of the obstruction.

One of the greatest difficulties encountered in the above outlined practice resides in 30 planting the whipstock in a properly centered and upright position, and in securely anchoring it in that position so that it will neither tilt nor rotate when met by the drill.

One common practice for planting and 35 cementing the whipstock in position has been simply to drop the whipstock in the well hole, and then follow it with a charge of cement, which cement is intended to fill in around the sides of and under the whipstock to form a substantial foundation 40 therefor.

One of the short-comings of the prior 45 practice arises from the fact that the whipstock is not positively held in any given position prior to or during the cementing operation, with the result that it often comes to rest and is set at an undesirable or even inoperative angle. Further, since in the prior practice the cement descends through the mud laden fluid in the otherwise open bore, it is often extremely difficult and

sometimes entirely impossible to get the charge of cement down through such fluid to the base of the whipstock, with the result that the whipstock is unanchored and therefore ineffective in the subsequent "side-tracking" efforts. 55

It is therefore the primary object of my invention to provide a method for anchoring a whipstock in cement in such a manner as to insure that the whipstock is initially supported in an upright or operative position and maintained in that position during the cementing operation, and to deliver the cement in such a manner that when set it will surround the whipstock in a manner to hold it in operative position during subsequent side-tracking operations. 60

In accordance with the present invention, I lower the whipstock to position in the well bore on the lower end of a pipe string, 70 and then, before detaching the whipstock, force a measured charge of cement down through the pipe string and into and through a communicating passageway in the whipstock, whence it is discharged under 75 pressure to the well bore, filling in below and well up around the sides of the whipstock. The cement may then be given time to set and harden, after which connection between the pipe string and whipstock may 80 be broken without disturbing the position of the latter; or, if there is any danger of the cement filling in around the top of the whipstock and making disconnection of the pipe string difficult, the connection is preferably broken before the cement has had 85 time fully to set. The pipe string is thereafter raised out of the well bore and the side tracking operations are carried out in the usual manner. 90

This application is a division of my co-pending application entitled "Whip-stock", filed November 1st, 1929, Ser. No. 403,968, wherein is disclosed and claimed the specific whipstock hereinafter illustrated and described in connection with the method claimed in the present case. 95

For the purpose of more fully disclosing the present invention, reference is now directed to the accompanying drawing show- 100

ing a whipstock designed for use in the present method, and wherein:

Fig. 1 is a vertical longitudinal section through the whipstock showing it attached to a pipe string above the obstruction to be avoided; and

Fig. 2 is a detached, plan view looking down on the whipstock proper; and

Fig. 3 is a view showing a whipstock in the lower end of a well bore, and showing the use of a plug for making known at the ground surface when the cement is all out of the whipstock.

In the drawing numeral 10 designates generally the well bore, in the lower end of which is an obstruction, illustrated in the present case as a lost tool 11. If the occasion requires, the first operation may consist in filling in cement above the lost tool 20 to form a solid support, indicated at 11a, upon which the whipstock may rest at its lower end. This cement filling may be taken as typical of any suitable support for the whipstock. The whipstock, generally designated by the numeral 12, is lowered to a position adjacent support 11a or obstruction 11, as the case may be, by means of a string of pipe 13. Where rotary drilling operations are employed, the drill pipe ordinarily is used for this purpose. The lower end of the drill pipe is coupled to a tool joint 14 to which is threaded a carrier fitting 15 for the whipstock proper. The whipstock proper comprises an elongated body 35 which may be rectangular in cross-section, as shown in Fig. 2, or of any other convenient form, having a beveled upper end providing a slanting drill-deflecting surface 17. Carrier fitting 15 has a lower tapered end providing a complementary lower slanting surface 18 in contact with surface 17, and the whipstock is supported from fitting 15 by means of relatively light frangible bolts 19 passing through the tapered 40 overlapping ends. The bolt heads are preferably countersunk in the side of the whipstock body so that they will not rub against the side of the well bore or the well pipe as the whipstock is lowered.

Fitting 15 and whipstock 12 are drilled with a longitudinal circulation bore or passageway 20 forming a continuation of the bore of the rotary drill pipe. As a manufacturing expedient, though not necessary to the invention, bore 20 may be extended through the bottom of the whipstock and then closed off at said bottom by a plug 32.

The lower end of fitting 15 is counter-bored at 24 and tapped to take a sleeve or nipple 25 which extends down into a corresponding counterbore 26 in the whipstock and rests at its lower end upon a rubber gasket 27 therein. There is thus provided a cheaply manufactured fluid tight joint for bore 20 between the fitting 15 and the whip-

stock proper, eliminating the necessity of accurately machining the two slanting faces 17 and 18.

The whipstock is provided with a lower reduced section 30 drilled with a number of lateral circulation holes or discharge passageways 31 through which fluid in passageway 20 can be discharged around the sides of the whipstock. These lateral discharge holes, which are preferably at the lower end of the whipstock body, as shown, are of a total area practically equivalent to the area of the main vertical passageway 20. It will be seen that body 12 may be considered as a hollow whipstock, with discharge passageways 31 leading from hollow 20 to the exterior of the whipstock.

The lower section 30 of the whipstock is provided with grooves 34 to provide for cement keys, when the cementing operation is carried out.

The method of setting the whipstock in cement is as follows: After lowering the whipstock to the desired point near or above obstruction 11 or support 11a, as the case may be, by means of the drill stem, a measured charge of cement is forced down by water pressure through the drill stem and circulation bore of the whipstock, and finally out through the circulation passages 31 to fill in around the lower end of the whipstock, as indicated at 38 in the drawing.

In certain situations a loose fitting plug is sent down on top of the cement charge; and the arrival of the plug at the lower end of the whipstock and consequent closure of the discharge openings creates back-pressure which is readily noticed at the ground surface and is taken as an indication that the cement charge is properly delivered. The plug also prevents the forcing water from driving the cement charge entirely clear of the whipstock, as it might otherwise do were the forcing operation to continue too long. Figure 3 represents such a situation, plug 50 having been sent down on top cement 38, separating said cement from the water 52, which is under pressure from above.

When the cement has had time to set, the drill pipe is released or disconnected from the whipstock by increasing the downward pressure on the drill stem causing fitting 15, intending to slide downwardly over face 17, to shear bolts 19 and sleeve 25, whereupon the drill pipe is lifted clear of the whipstock and out of the well bore, leaving the whipstock set in the cement. Or, if there is danger of the cement rising above the upper end of the whipstock and rendering final disconnection of the pipe string from the whipstock difficult, said disconnection is preferably made before the cement has had time fully to set and harden.

The following operations of drilling against the upper deflecting surface 17 of

the whipstock so that the drill is sidetracked about the obstruction are well understood in the art and need no detailed description.

No difficulty ensues if the filled-in cement 5 rises above the level indicated in the drawing to a point above the upper end of the whipstock, provided the drill pipe is disconnected before the cement has fully set and hardened, for the bit will merely drill 10 down through the surplus cement and when it strikes the upper surface of the whipstock will be turned aside as before.

It will be now seen that I have provided a method for supporting a whipstock in up- 15 right or operative position until cemented in, and for surrounding the lower end of the whipstock with a solid bed of cement. Thus the method provides for accurate placing of the whipstock, as well as assur- 20 ing that it will be solidly set in cement to maintain it in that position. Heretofore when it has been endeavored simply to pour cement down around a whipstock it has been the common experience that the cement will 25 not pass down below the head of the whip- stock because of the heavy mud which is entrapped around and below the whipstock. By delivering the cement initially under pressure to a point or points around the lower 30 end of the whipstock it is assured that the whipstock is well set, all of the mud around its base being displaced by cement. The cement first envelopes the lower end of the whipstock and then flows upwardly 35 around it. Thus the whipstock is given a perfect foundation at its lower end.

It will be understood the drawing and description are to be considered merely as illustrative of and not restrictive on apparatus which may be used in connection with the method of the present invention, and that said invention is to be limited only as defined in the following claims.

I claim:

45 1. The method of setting a hollow whip- stock in a well bore, that includes lowering the whipstock to position in the well bore on the lower end of a pipe string, forcing cement down through the pipe string 50 into the hollow of the whipstock and thence through openings in the whipstock to the exterior thereof, whereby the cement surrounds at least a portion of the whipstock, allowing the cement to set, and then disconnect- 55 ing the pipe string from the whipstock, and removing the pipe string, leaving the whip- stock set in the cement.

2. The method of setting in a well bore a whipstock having a longitudinal passage 60 therein, that includes lowering the whip- stock to position in the well bore on the lower end of a pipe string, forcing cement down through the pipe string and through the whipstock and discharging said cement 65 near the lower end of the whipstock to the

well bore, whereby the cement surrounds at least a portion of the whipstock, allowing the cement to set, and then disconnecting the pipe string from the whipstock, and removing the pipe string, leaving the whip- stock set in the cement. 70

3. The method of setting a whipstock in a well bore, that includes lowering the whip- stock to position in the well bore on the lower end of a pipe string, forcing cement down through the pipe string into and through a longitudinal passage in the whip- stock and through lateral discharge open- 75 ings leading from said passageway to the well bore near the lower end of the whip- stock, whereby the cement surrounds the lower portion of the whipstock, allowing the cement to set, then disconnecting the pipe string from the whipstock, and removing the pipe string, leaving the whipstock set 80 in the cement. 85

4. The method of setting a hollow whip- stock in a well bore, that includes lowering the whipstock to position in the well bore on the lower end of a pipe string, forcing cement down through the pipe string into the hollow of the whipstock and thence through openings in the whipstock to the exterior thereof, whereby the cement surrounds at least a portion of the whipstock, and subsequently disconnecting the pipe string from the whipstock and removing the pipe string, leaving the whipstock embed- 90 ded in the cement. 95

5. The method of setting in a well bore a hollow whipstock having discharge open- 100 ings from said hollow to the exterior of the whipstock, that includes lowering the whip- stock to position on the lower end of a pipe string, introducing a measured quantity of cement to the pipe string, following said quantity of cement with a plug adapted to slide through said pipe and to hold the pressure in the pipe string above when it reaches a position at the whipstock, forcing said cement and plug down to the whip- stock, and said cement through the whip- stock hollow and out said discharge open- 105 ings whereby the cement surrounds at least a portion of the whipstock, and subsequently disconnecting the pipe string from the whipstock and removing the pipe string, leaving the whipstock embedded in the ce- 110 ment. 115

6. The method of setting in a well bore a hollow whipstock having discharge open- 120 ings from said hollow to the exterior of the whipstock, that includes lowering the whip- stock to position on the lower end of a pipe string, introducing a measured quantity of cement to the pipe string, following said quantity of cement with a plug adapted to slide through said pipe and to close off said discharge openings when it is within the whipstock hollow, forcing said cement and 125

- plug down and into the hollow, and said cement out through said discharge openings whereby the cement surrounds at least a portion of the whipstock, until said plug 5 seats in said whipstock hollow, allowing the cement to set, then disconnecting the pipe string from the whipstock, and removing the pipe string, leaving the whipstock set in the cement.
- 10 7. The method of setting in a well bore a hollow whipstock having discharge openings from said hollow to the exterior of the whipstock, that includes lowering the whipstock to position on the lower end of a pipe 15 string, introducing a measured quantity of cement to the pipe string, following said quantity of cement with a plug adapted to slide through said pipe and to hold the pressure in the pipe string above when it reaches 20 a position at the whipstock, forcing said cement and plug down to the whipstock, and said cement through the whipstock hollow and out said discharge openings whereby the cement surrounds at least a portion 25 of the whipstock, allowing the cement to set, then disconnecting the pipe string from the whipstock, and removing the pipe string, leaving the whipstock set in the cement.
- 30 In witness that I claim the foregoing I have hereunto subscribed my name this 31st day of October 1932.
